UNITED STATES PATENT OFFICE.

MARTIN PELZ, OF NEW YORK, N. Y.

NON-REFILLABLE BOTTLE.

979,998.

Specification of Letters Patent. Patented Dec. 27, 1910.

Application filed August 31, 1910. Serial No. 579,800.

To all whom it may concern:

Be it known that I, MARTIN PELZ, a subject of the German Emperor, and a resident of the city of New York, in the county 5 of Kings and State of New York, have invented certain new and useful Improvements in Non-Refillable Bottles, of which the following is a specification.

The present invention relates to non-refillable bottles for holding proprietary beverages and other fluids, and being provided with devices located in the neck of the bottle, permitting the same to be emptied, but not refilled.

One of the objects of the invention is to produce a non-refillable bottle capable of manufacture on a commercial scale, in other words which is not so difficult to produce as to be beyond the reasonable cost of such 20 an article.

With these and other objects in view, which will fully appear as the nature of the invention is better understood, the same consists in the construction, arrangement 25 and combination of the parts hereinafter fully described, pointed out in the appended claim and illustrated in the accompanying drawings, it being understood that various changes may be made in the 30 size and proportion of the several parts and minor details of construction without departing from the spirit or sacrificing any of the advantages of the invention.

One of the many possible embodiments of 35 the invention is illustrated in the accompanying drawings, in which:—

Figure 1 is a vertical section of a bottle neck containing the device forming the subject matter of the present invention; Fig. 40 2 is a section taken on line 2, 2 of Fig. 1; Fig. 3 is a section taken on line 3, 3 of Fig. 1; and Fig. 4 is a plan view of a detail of construction.

In the drawings, the numeral 5 denotes 45 a bottle which is made of any suitable material and of any desired shape, and is provided with the usual neck 6, having in its inner surface near to its outer end an annular groove 7, for a purpose hereinafter to 50 be specified. A shoulder 8 is provided around the middle section of the neck, upon which rests a ring 9, preferably made of cork, the outer diameter of which corresponds exactly to the inner diameter of the 55 neck 6. In the bore of this ring is fixedly

mounted a tubular valve casing 10, which may be made of a non-corrodible metal or of glass; its walls being of a thickness to produce a rigid structure. This valve casing is closed at its lower end by means of a 60 cover 11, which may be either fastened to the same in any suitable manner or may be made integral therewith. Slots 12 are provided a suitable distance above the cover 11 in the valve casing, and a plurality of openings 13 near to its upper end 14, which is open. A valve seat 15 is formed below the openings 13 upon the inner wall of the casing 10, and upon this seat is arranged a valve disk 16, fastened in any suitable manner to a stem 17, which is guided in its movement by a spider 18 and a hole 19 in the cover 11. A small disk 20 is attached to the valve stem within the casing 10, and against this disk and the spider 18 bears a 70 spring 21, keeping the valve upon its seat 15. The valve stem projects through the hole 19 out of the casing 10, and is provided there with a curved plate 22. Below this plate is arranged a disk 23, held by means of 80 a bent wire 24, which is attached to said disk and to the valve casing 10, in a substantially horizontal position and at the proper distance below the curved plate 22. From the disk 23 depends a ball 25, preferably of glass filled with a heavy metal, and held upon the disk 23 by means of a 85 flexible connection 26.

A perforated plate member 27, the outer diameter of which corresponds to the inner 90 diameter of the neck 6, is provided with a channel 28, running diametrically therethrough and at right angles to the longitudinal axis thereof. In the channel 28 are arranged two plugs 29, 29, against which 95 bears a spring 30, arranged in said channel, whereby as the plate member is forced downward into the neck of the bottle, the spring pressed plugs 29 will engage the annular groove 7 in said neck and keep the 100 said plate member irremovably in position therein.

Instead of the usual cork, a screw bolt 31 is provided, the threads of which mesh with the threads of the perforation 32 in 105 the plate member 27. The outer end of this screw bolt is provided with wings 31' for a well known purpose. The inner end of the bolt 31 bears against the valve disk 16.

The operation of the device is as follows: 110

The bottle is first filled with liquid, and the valve casing 10 with its appurtenances is then pushed down until its ring 9 comes to rest upon the shoulder 8, after which the 5 closing disk 27 is inserted into the neck, whereby its plugs 29 will enter the annular groove 7, holding thereby said closing disk irremovably in the neck of the bottle. In arranging the screw bolt 31 in the manner 10 hereinbefore described upon the disk 27, the bottle is ready for transportation. Unscrewing the bolt 31, and inverting the bottle will cause the ball 25 to be brought to rest upon the curved plate 22, compressing 15 thereby spring 21 and unseating the valve disk 16. The contents of the bottle entering the valve casing 10 may then escape through the openings 13 in said valve casing and through the perforations of the disk 27, so 20 that the contents may be freely poured from the bottle; but if attempt is made to refill, the spring 21 will seat the valve 16, so that the liquid will not flow into the bottle. The closing disk 27 prevents access to the valve 25 by wires or other devices, so that the valve cannot be tampered with.

It will be observed that a shaking of the bottle will not unseat the valve, the disk 23

30 preventing the ball 25 from acting upon the curved plate 22.

The device is extremely simple both in construction and action, and consequently can be produced at very low cost.

What I claim is:

35 In a non-refillable bottle, the combination with the neck of a bottle, of a tubular valve casing therein provided with a plurality of openings near its upper end and a plurality of openings near its lower closed end, a valve seat below the openings which are 40 arranged near the upper end of said valve casing, a valve upon said seat, a valve stem attached to said valve and projecting through and below the closed end of said valve casing, resilient means for holding 45 said valve upon its seat, a disk attached to said valve casing below the lower end of said stem, a ball and a flexible connection between said ball and said disk.

Signed at New York, in the county of New 50 York and State of New York, this 19th day of August, A. D. 1910.

MARTIN PELZ.
